ATTORNEY

UNITED STATES PATENT OFFICE.

ALBERT E. PATRICK, OF SACRAMENTO, CALIFORNIA.

OIL BURNER.

Application filed March 21, 1923. Serial No. 626,560.

To all whom it may concern:

Be it known that I, ALBERT E. PATRICK, a citizen of the United States, residing at Sacramento, county of Sacramento, State of California, have invented certain new and useful Improvements in Oil Burners; and I do declare the following to be a full, clear, and exact description of the same, reference being had to the accompanying drawings, and to the characters of reference marked thereon, which form a part of this application.

This invention relates to improvements in oil burners, and particularly to a type adapted to burn light fuels, such as stove distillate, kerosene, gasoline, etc., and is especially intended to be used in hot air furnaces and other heating plants, and with low-pressure steam boilers.

The principal objects of my invention are to provide a burner of this type which may be used with either natural or forced draft, and with the latter draft will develop many times its normal heat in a very short space of time; one with which a check-draft may be used, in connection with either natural or forced draft; one in which no carbon will form in the fuel or vaporizing chamber; one in which a fire of equal intensity is formed all around the vaporizing chamber while the supply pipe is out of the direct line of heat; one in which the flow of fuel may be regulated to give the right mixture regardless of the kind of draft; one which is extremely economical in its fuel consumption, and one which may be installed in any furnace, and any part, if necessary, can be easily removed and inspected without taking out any lengths of piping, etc.

The burner is also very simple in construction having few parts, and is compact, and inexpensive to manufacture, and will last a long time without replacement of any parts.

These objects I accomplish by means of such structure and relative arrangement of parts as will fully appear by a perusal of the following specification and claims.

In the drawings similar characters of reference indicate corresponding parts in the several views.

Fig. 1 is a side elevation of the burner.

Fig. 2 is a sectional elevation of the same. Referring now more particularly to the characters of reference on the drawings, the

numeral 1 denotes a hollow bell-shaped body, the lower flange 2 of which is adapted to rest on any furnace grate. Drilled radially through the upper portion of the body all around the same are equally spaced horizontal holes 3, in two or more vertical rows, depending on the size of the burner, the upper row having the largest holes, which are drilled as close to the top face or wall 4 of the body as possible, said wall being substantially flat, and having a shoulder 5 set in a certain distance from the outer periphery of the body.

A fuel supply pipe 6 is screwed into the wall 4 centrally thereof, and discharges onto the top of the same.

Removably and closely seated on top of the body 1 outside the shoulder 5 and centrally located thereby is an inverted cup 7, provided with a plurality of vertical and radial slits 8 cut upwardly a certain distance from the lower edge thereof, and at intervals all around the same, the slits being located centrally above certain of the upper holes 3.

The space enclosed between the cup and body wall 4 forms the fuel or vaporizing chamber 9 and theoretically the cup could be formed as one with the body, but for obvious reasons it is made as a separate member, being removable when cleaning out is necessary, and being more easily and cheaply manufactured.

In operation, fuel is allowed to flow into the chamber 9, and is initially heated to the vaporizing point by any suitable means, such as by the application of a blow torch, waste paper, or other material, to the body and cup.

The vaporized fuel can only escape through the slits 8, and is ignited by contact with the burning initial heating means. The ignited jets of fuel are immediately mixed with the air passing up inside the body and out through the horizontal holes 3, the amount of fuel allowed to pass into the chamber being regulated according to the amount of air or draft available or being used.

It will thus be evident that the fire thus had is of equal intensity all around the body, and that it will be directly away from the vaporizing chamber, while at the same time sufficient heat is of course thrown against the cup to keep the fuel flowing therein vaporized.

The cup and chamber, however, as well as the supply pipe, are out of the direct line of heat, and will be maintained relatively cool, a condition which is helped by reason 5 of the fact that the cold air, before passing through the holes 3 to mix with the fuel, impinges against the bottom of the fuel chamber, as well as surrounding the fuel pipe. By thus keeping the fuel chamber automatically cool, the formation of carbon therein 10 and in the feed pipe, which is one of the main defects and sources of annoyance and tie-ups with various other burners, is eliminated, as I have found from tests covering 15 several days of continuous performance.

The design of the burner is such that forced draft may be used therewith, the fuel chamber, in spite of the greater volume and intensity of the fire, being maintained in its 20 cool condition, since a greater volume of the cold incoming air is being directed against the bottom of the chamber to counteract the effect of the greater heat being transmitted thereto.

25 A "check draft," such as causes a good many oil burners to function very unsatisfactorily, may also be used with my burner without any trouble.

Nothing but air passes through the holes 30 3, and it will be seen that should the slits 8 ever become choked up, the cup 7 may be instantly removed for cleaning without disturbing any other member.

From the foregoing description it will 35 be readily seen that I have produced such a device as substantially fulfills the objects of the invention as set forth herein.

While this specification sets forth in detail 40 the present and preferred construction of the device, still in practice such deviations

from such detail may be resorted to as do not form a departure from the spirit of the invention, as defined by the appended claims.

Having thus described my invention, what I claim as new and useful and desire to secure by Letters Patent is:

1. An oil burner comprising a hollow body open on its lower end and having an enclosed chamber at its upper end, a fuel pipe connected to said chamber, horizontal air passages through the wall of the body under the chamber, and fuel passages through the sides of the chamber above and in substantially the same vertical plane as 55 said air passages.

2. An oil burner comprising a hollow body open on its lower end and covered on its upper end, a fuel pipe leading up inside the body and connected thereto to discharge on top of the body, horizontal orifices through the body-wall just under the top wall thereof, and an inverted cup removably seated on top of the body and forming an enclosed chamber therewith, said cup having a plurality of radial slits in its side extending upwardly from the lower edge thereof, the outer ends of the slits and air passages lying in a substantially common vertical plane.

3. An oil burner comprising a one-piece body formed as an inverted cup terminating at its lower end in an outwardly flaring and substantially horizontal flange, a removable inverted cup having a snug fit on top of the body and forming an enclosed chamber therewith, and horizontally disposed and spaced passage means through the body-cup and chamber-cup walls.

In testimony whereof I affix my signature:
ALBERT E. PATRICK.
